UNITED STATES PATENT OFFICE.

BENJAMIN N. BRCIDO, OF NEW YORK, N. Y., ASSIGNOR TO THE SUPERHEATER COMPANY, OF NEW YORK, N. Y., A CORPORATION OF DELAWARE.

SEPARATELY-FIRED SUPERHEATER.

Application filed June 17, 1924. Serial No. 720,476.

This invention relates to superheaters and particularly to separately fired superheaters in which the superheater units are heated by the gases from a furnace forming a part of 5 the superheater installation, as distinguished from that type of superheaters in which the elements are installed in the main boiler of the plant.

The principal object of this invention is to 10 provide a new and improved construction in a device of the character described by means of which the superheater units are protected from overheating.

Other more specific objects of my invention 15 will be apparent to one skilled in the art to which it appertains from the following more detailed description and by reference to the accompanying drawings forming a part thereof and wherein an example of my invention 20 is illustrated without defining its limits.

In the drawings:

Fig. 1 is a longitudinal vertical section on the line 1—1 of Fig. 2 and Fig. 2 is a transverse vertical section, the right hand half 25 thereof being taken on the line Y—Y of Fig. 1 and the left hand half on the line X—X of Fig. 1.

As shown in the drawings the apparatus comprises a furnace 10 which is separated 30 from the superheating chamber 11 by means of a transversely extending fire wall 12 which terminates a short distance from the top wall 13 of the apparatus to define an inlet passage 14 for the furnace gases.

As shown in Fig. 2, the superheating chamber 11 is provided with a reinforcing wall 15 which extends longitudinally down the center of the chamber and divides it into two similar halves. A plurality of baffle walls 16

40 and 17 extend transversely across the chamber from the reinforcing wall 15 to the side walls 18, to provide a tortuous passage for the furnace gases from the inlet 14 to the outlet 19 in the rear wall 20 of said chamber.

45 The baffle walls 16 extend upwardly from the floor of said chamber and terminate a short distance from the top 13 thereof, said walls increasing gradually in height from the front to the rear of the chamber; while 50 the baffle walls 17 extend downwardly from the top and terminate in the arch shaped ends 21 a short distance from the floor of said chamber.

In the example of the invention illustrated 55 I provide a pair of inlet headers 22, 23 locat-

ed respectively adjacent to the front and rear of the chamber 11, an outlet header 24 located adjacent to the center of said chamber, and a connecting header 25, 25^a between each inlet header and the outlet header; said headers extending transversely across the top of the apparatus and being supported by any suitable supporting structure such as the uprights 26 and cross beams 26^a.

A plurality of rows of superheater units, 60 having their ends connected to the headers, are supported by said headers and extend downwardly into the chamber 11 from the top thereof.

In order to protect the superheater elements from overheating, the units with which the hot gases first come into direct contact are protected by interpolating some superheater surfaces ahead of them with which the gases do not come into direct contact, but which 70 surfaces are exposed to the hot gases so as to receive some of the heat from the gases by radiation. The heat exchange between the gases and these interpolated surfaces insures a cooling of the gases to a point such that 75 the gases may safely be allowed to sweep over and in direct contact with the next superheater surfaces.

A suitable arrangement as shown in the drawings consists in placing the major rear 80 portion of the superheater, comprising the looped tubes or units 27, 27^a and 28^b, directly in the path of the furnace gases in accordance with the usual practice, the loops thereof extending parallel to the side walls. The 85 remaining front portion of the superheater (preferably the first one or two rows) is arranged out of the direct path of the gases. This is accomplished by placing the first two rows of units 28, 28^a, so that the loops extend transversely of the chamber 11 and closely adjacent to the baffle wall 17.

The hot furnace gases are deflected from the rows of tubes 28 by a fire brick arch 35 which is spaced slightly from the baffle wall 100 and extends across outside of the tubes 28 approximately opposite to the top of the fire wall; the upper edge of the arch 35 preferably extending a trifle higher than the fire wall. A projecting arch-shaped ledge 36 extends laterally from each side of the lower arch-shaped bottom edge 21 of the first baffle wall 17; the forwardly extending ledge 36 co-operating with the arch 35 to prevent direct contact of the furnace gases with the first 105 110

row of tubes 28 and the rearwardly extending ledge deflecting the gases towards the opening at the upper end of the second baffle wall 16 to prevent their direct contact with the second row of tubes 28^a.

In the example shown it will be seen that the steam flow through the superheater units is divided into two separate passes, a front pass and a rear pass. In the rear pass the saturated steam is introduced into the header 23, from which it passes through the units 27 to the intermediate header 25^a, thence through the units 27^a and is withdrawn in superheated condition through the outlet header 24; the flow of the steam in this rear pass being substantially counter to the flow of the furnace gases. The flow of the steam in the front pass is substantially parallel to the gas flow; saturated steam being introduced into the units 28, flowing thence to the units 28^a, then to the intermediate header 25 from which it is distributed to the units 28^b and flows from these last named units to the outlet header 24.

It will be understood that various changes and modifications of the structure herein disclosed may be resorted to without departing from the spirit of my invention.

I claim:

1. In a superheater, a furnace, a superheating chamber having an inlet communicating with said furnace and an outlet; a plurality of superheater tubes extending within said chamber in the direct path of the furnace gases, a baffle wall extending partially across said chamber adjacent to said inlet, a ledge projecting from each side of the bottom of said wall, a deflecting surface extending across one side of said wall opposite said inlet, said ledge and deflecting surface forming with said baffle wall a pair of pockets located out of the flow of the gases from said furnace, and a plurality of superheater units extending along each side of said baffle wall within said pockets.

2. In an apparatus of the character described, a furnace, a chamber having an inlet communicating with said furnace and an outlet; a plurality of fluid heating tubes extending within said chamber in the direct path of the furnace gases, a baffle wall extending partially across said chamber adjacent to said inlet, a plurality of ledges projecting from said wall, said ledges forming with said baffle wall a pair of pockets located out of the flow of the gases from said furnace, and a plurality of fluid heating units extending along the side of said baffle wall within said pockets.

3. In an apparatus of the character described, the combination of a furnace, a heating chamber in communication with said furnace through which the furnace gases pass, and a fluid heating device in said chamber comprising heating tubes arranged to form a plurality of separate parallel passes, the ma-

jority of said tubes being located in the direct path of gases from the furnace and the remaining tubes forming a separate parallel pass located out of the furnace and out of the direct path of the gases but exposed to radiation from them, said remaining tubes being heated only by the radiant heat of the furnace gases and serving to cool said gases before they contact with said majority of tubes, and the gases passing directly from said remaining tubes to said majority of tubes without contacting with any intervening heat exchange surfaces.

4. In an apparatus of the character described, the combination of a furnace, a heating chamber in communication with said furnace through which the furnace gases pass, and a fluid heating device comprising a plurality of heating units in said chamber arranged in two separate passes connected in parallel, one of said passes being located in the path of the gases from the furnace in their passage through the chamber and the other pass being located nearer to, but out of the furnace and having the major portion thereof not within the direct path of the gases but exposed to radiation from them, said other pass serving to cool the furnace gases before they contact with the units of said first named pass.

5. In an apparatus of the character described, the combination of a furnace, a heating chamber in communication with said furnace through which the furnace gases pass, a plurality of baffle walls projecting into the chamber to provide a tortuous passage for the furnace gases through the chamber, and a fluid heating device comprising a plurality of heating units forming separate passes connected in parallel, the major portion of said units being arranged in said tortuous passage in the direct path of the gases, and the remaining portions forming a separate pass interpolated in said passage between said major portion and the furnace, said remaining portions being arranged out of the direct path of the gases but exposed to radiation from them, and serving to cool the furnace gases before they contact with said major portion.

6. In an apparatus of the character described, a furnace, a chamber in communication with said furnace through which the furnace gases pass, a plurality of fluid heating tubes mounted within said chamber at different distances from said furnace and connected to form separate parallel passes, those tubes which are located in closest proximity to the furnace forming a separate pass and being arranged out of the direct path of the furnace gases to receive heat therefrom by radiation and to cool said gases and the remaining tubes being arranged within the direct path of the gases.

7. In an apparatus of the character described, a furnace, a chamber having an inlet

communicating with said furnace and an outlet; a plurality of baffle walls projecting into said chamber to provide a tortuous passage for the furnace gases through said chamber 5 from said inlet to said outlet, a plurality of fluid heating tubes mounted within said chamber in spaced rows at different distances from said furnace, and connected to form separate parallel passes, the major portion of 10 said tubes extending into said passage within the direct path of the furnace gases to be heated thereby by convection, and the remaining tubes being located nearest to said furnace and forming a separate pass, a plurality of deflecting surfaces adjacent to said remaining tubes to prevent direct contact of the furnace gases therewith, whereby said remaining tubes will absorb heat from said gases substantially by radiation only, and will also 15 serve to cool said gases before they are permitted to contact with the major portion of 20 said tubes.

8. In an apparatus of the character described, the combination of a furnace, a heating chamber in communication with said furnace through which the furnace gases pass, a fluid heating device in said chamber comprising a plurality of heating units arranged to form a first pass and a rear pass separate from said first pass, a plurality of headers arranged to cause the fluid to be heated to flow through said first pass parallel with the gas flow and through said rear pass counter to the gas flow, the units of said rear pass being located within the direct path of the furnace 25 gases, and the major portion of the units of said first pass nearest to the furnace being located out of the direct pass of the furnace gases but exposed to radiation from them and serving to cool the furnace gases before 30 they sweep over the units of the rear pass.

In testimony whereof I have hereunto set my hand.

BENJAMIN N. BROIDO.
